(57) **CLAIM**

The ornamental design for a cap, as shown and described.

DESCRIPTION

FIG. 1 is an isometric view of the cap, embodying the new design;

FIG. 2 is a left view thereof;

FIG. 3 is a right thereof;

FIG. 4 is a front view thereof;

FIG. 5 is a back view thereof;

FIG. 6 is a top view thereof; and,

FIG. 7 is a bottom view thereof.

The broken lines in the drawing showing of the neck of the cap depict environmental subject matter only and form no part of the claimed design.
